UNITED STATES PATENT OFFICE.

EDWIN R. BRANSON, OF PHILADELPHIA, PENNSYLVANIA, AND EUGENE E. DAVIS, OF ROCKFORD, ILLINOIS, ASSIGNORS TO SAID BRANSON.

CIRCULAR-KNITTING MACHINE.

SPECIFICATION forming part of Letters Patent No. 594,062, dated November 23, 1897.

Application filed July 29, 1895. Serial No. 557,544. (No model.)

To all whom it may concern:

Be it known that we, EDWIN R. BRANSON, of the city and county of Philadelphia, in the State of Pennsylvania, and EUGENE E. DAVIS, of the city of Rockford, county of Winnebago, and State of Illinois, have invented certain new and useful Improvements in Circular-Knitting Machines, of which the following is a specification.

10 Our invention relates specifically to mechanism for controlling the yarn that is customarily employed to reinforce the heels and toes of stockings by conducting it to and withdrawing it from the fashioning-needles of knitting-machines at predetermined intervals.

Our invention also relates to combined devices for stopping knitting-machines either automatically or at the will of the operator.

20 Our invention consists of certain new and useful features of construction and combinations of parts hereinafter described, and pointed out in the claims.

Referring to the accompanying drawings, 25 which form a part of this specification, Figure 1 is a side elevation of a knitting-machine provided with our improvements having their parts so adjusted as to adapt them to conduct the reinforcing-yarn to the machine fashioning-needles. Fig. 2 is an enlarged view in detail of parts shown in Fig. 1. Fig. 3 is a side elevation of the machine, Fig. 1, showing the controlling devices holding a thread of reinforcing-yarn withdrawn from the machine-needles.

30 Fig. 4 is a front elevation of the same. Fig. 5 is an enlarged front elevation in detail of parts shown in Fig. 4 and other views of the drawings. Fig. 6 shows our improvements adapted and applied to a machine the needles whereof are arranged in parallel rows. Fig. 7 is a side elevation of a machine furnished with our yarn-controlling mechanism and mounted on a table or framework provided with our improved devices

45 for stopping the same. The pattern-wheel, ratchet-wheel, and pallet and detent shown therein are modifications of those shown in Figs. 1 and 3. Fig. 8 is a plan view of the last-mentioned machine. Fig. 9 is a detailed 50 view of parts shown in Figs. 7 and 8. Figs.

10 to 12, inclusive, are sectional details at the dotted line X X in Fig. 2, illustrating the mode of operation of the combined devices there shown.

Like letters of reference indicate corresponding parts throughout the several views.

A is the needle-cylinder of the machine, which is provided with needles A'.

A² is a vertical standard secured to the top of the machine-frame.

A³ is a yarn-carrier projecting horizontally from the standard A².

B is a pattern-wheel, the periphery whereof is indented by the shoulder B', step B², incline B², and depressed circular portion B³, the three former connecting the latter with the periphery proper of the wheel.

B⁴ is a ratchet-wheel mounted on the shaft B⁵.

C is an oscillatory arm, the upper end whereof is pivot-jointed to the shaft B⁵.

C' is a spring-actuated pallet for driving the pattern-wheel B through the ratchet-wheel B⁴.

C² is a detent for locking the pattern-wheel B through the ratchet-wheel B⁴.

The pallet C' and detent C², Figs. 1 and 3, are thrown out of engagement with the ratchet-wheel B⁴ by the operator, which will cause the latter to remain motionless during the knitting of the last portion of the leg of a stocking.

D is a shaft having the eccentric D' mounted fast thereon.

D² is a driving-arm pivoted by one end to the lower end of the oscillatory arm C and by the other end to the eccentric D'.

E is one arm of the thread-controller, rigidly secured to the standard A² or other suitable support and provided with an open eye E' in the upper end thereof. A closed eye may be substituted for the open eye E', if desired.

F is the other arm of the thread-controller, pivot-jointed at or near its lower end to the standard A² or other suitable support, provided with an actuating-lug F', projecting outwardly into engagement with the periphery of the pattern-wheel B and having an open eye F² in the upper end thereof. A closed

eye may be substituted for the open eye F², if desired.

5 F³ is a yarn-chute fast to one of the controller-arms, as F, and having an eye F⁴ thereto in adjacent to the eye F² for the passage of the reinforcing-yarn therethrough.

G is a thread of yarn that is continuously employed in the operation of knitting.

10 G' is a thread of yarn that is intermittently provided to reinforce the heels and toes of stockings as the same are being knit.

H are yarn-guides of any suitable form and construction.

15 I is a spring holding the free end of the lug F' into constant engagement with the periphery of the pattern-wheel B.

J is the top of a knitting-machine table.

20 J' J² are respectively fast and loose pulleys mounted on the main shaft D of the machine.

J⁴ is a bar mounted in the bearings J⁵ so as to slide longitudinally therein.

J⁶ is a belt-shipper fast to the sliding bar J⁴.

25 J⁷ is a spring which holds the belt-shipper J⁶, when normal, over the loose pulley J².

K is a longitudinally-sliding detent held into engagement with the bar J⁴ by means of a spring K', having one end thereof adapted to fit into the notch J⁸ therein and hold the 30 belt-shipper J⁶ over the fast pulley J'. The other end of the detent K has an open slot K² therein, the side K³ whereof inclines obliquely backward and upward, thereby leaving the upper portion of the slot narrower than its lower portion.

35 K⁴ is a pin inserted through and fast in the detent K.

L is a rotatable cam provided with a pin L', adapted to engage with the incline K³ of the 40 slot K² in the detent K.

M is a crank mounted on the shaft B⁵ and provided with a pin M', adapted to engage with and rotate the cam L a half-revolution for each revolution of the pattern-wheel B 45 and shaft B⁵.

N is a lever for operating the belt-shipper J⁶ by hand.

O, Fig. 6, are the corresponding halves of a two-part needle-bed provided with needles 50 arranged in parallel rows therein.

P is a worm-wheel fast to the shaft B⁵, which drives the pattern-wheel B.

Q is a worm meshing with the worm-wheel P.

55 R is a shaft whereon the worm Q is mounted.

R' is a crank for operating the machine illustrated in Fig. 6.

The machine is operated as follows: While it is knitting the leg of a stocking the pattern-wheel B is motionless after the lug F' has traversed the depressed portion B³ thereof, the free end of the actuating-lug F' resting upon the depressed portion B³ thereof, just at the base of the incline B², and the parts F 60 and F³ being in the positions shown in Fig. 3 when knitting the first portions of the leg and foot of a stocking. When the knitting

of the leg is completed, about one-half of the needles go out of action, those remaining in action commonly being known as "fashioning-needles," the pattern-wheel B is caused to revolve, and the free end of the actuating-lug F' engages with and travels up the incline B², thereby causing the parts F and F³ to assume the positions shown in Figs. 1, 5, and 70

10, the free end of the lug F', however, being in engagement with that portion of the periphery of the pattern-wheel B⁶ adjacent to the incline B² instead of the position shown in Fig. 1. The reinforcing-yarn G', Figs. 1, 75

2, and 10, being then free is engaged by the yarn G, which forms the leg and round part of the foot of the stocking, and travels to the 80 needles all the time that the machine is in operation and is conducted down the chute F³ 85 to the fashioning-needles, which knit both threads of yarn G' in forming the reinforced heel of the stocking. The machine continues to knit the heel as long as the actuating-lug F' rests on the more elevated portion of the 90 periphery of the pattern-wheel B. When the pattern-wheel B has turned until the lug F' reaches the point B⁶ thereon, Fig. 1, it descends and rests upon the shoulder B', the parts F F³ thereupon assuming the positions 95 shown in Fig. 11 and gripping the thread G', as shown, thus causing it to be broken by tension at or near the needles. As the pattern-wheel B continues to turn, the lug F' descends until it rests upon the depressed portion B³ 100 thereof. This last descent of the lug F' throws the parts F F³ into the positions shown in Figs. 3 and 12, thereby completely withdrawing the free end of the broken reinforcing-yarn G' from contact with and the operation 105 of the fashioning-needles of the machine. As the lug F' descends to the position last mentioned the needles that went out of action when the operation of knitting the heel of the stocking began come into action again. The pattern-wheel B continues to turn and the free end of the lug F' traverses the entire 110 depressed portion B³ thereof, during which time the round part of the foot of the stocking is knit from the yarn G. The lug F' reaches 115 the foot of the incline B² a second time and ascends the same. The yarn G', Figs. 2 and 10, is again released preparatory to being conducted to the fashioning-needles to reinforce the toe of the stocking, which is knit in 120 precisely the same manner as the heel. Upon the completion of the toe of the stocking the mechanism that controls the reinforcing-yarn G' is at rest until the leg of another stocking 125 has been knit. The pattern-wheel B, shaft B⁵, and crank M make one complete revolution while the heel and the first portion of the foot of a stocking is being knit. The crank M in the course of such revolution engages, through the pin M', with the cam L and turns 130 it a half-revolution. After the round part of the foot of a stocking is completed the pattern-wheel B, shaft B⁵, and crank M make another complete revolution to knit the toe

and the first portion of the leg of the succeeding stocking. Figs. 8 and 9 show the crank M just as it is completing the second revolution, the toe of the stocking being finished.

5 The parts shown in detail in Fig. 9 are so arranged and timed in Figs. 7 and 8 with reference to each other that at the moment a stocking is completed the pin M' will engage with the cam L and turn it until the pin L' 10 projecting therefrom engages with the incline K³ on the detent K and slides it endwise out of the notch J⁸ in the sliding bar J⁴, thereby permitting the spring J⁷ to slide the latter inward until the belt (not shown) that drives 15 the machine is shipped from the driving-pulley J' onto the loose pulley J², which series of operations automatically stop the knitting-machine at the completion of each stocking. Whenever the operator wishes the machine to 20 knit another stocking, he ships the belt back to the driving-pulley J'. If it is desired to stop the machine by hand, the lever N must be swung from the pulley J² until the arm N' thereon engages with the pin K⁴ and thereby with- 25 draws the detent K from engagement with the notch J⁸ in the bar J⁴, whereupon the force of the spring J⁷ will ship the belt from the driving-pulley J' onto the loose pulley J².

We claim—

30 1. In a knitting-machine, in combination, a pair of arms pivoted one upon the other, one arm being stationary, each arm having an eye therein, adjacent to the other, where- 35 through yarn may pass at predetermined in- tervals, to reinforce the heels and toes of stockings, by reason of the alternate opening and shutting of said arms and a pattern-wheel for alternately opening and closing the same, substantially as and for the purpose specified.

40 2. In a knitting-machine, in combination, a pair of arms pivoted one upon the other, one arm being stationary, each of said arms having an eye in the free end thereof to ad- 45 mit the passage of yarn therethrough, and a yarn-chute, fast to the upper portion of one of said arms and having an eye therein, op-

posite to the eyes in said arms, substantially as and for the purpose specified.

3. In a knitting-machine, in combination, a stationary arm, an additional arm pivoted thereto and provided with an actuating-lug projecting therefrom, a chute secured to the upper portion of the movable arm, each arm and the chute having eyes therein, to admit the passage of yarn therethrough, and a pattern-wheel for actuating the movable arm at predetermined intervals, substantially as and for the purpose specified. 50

4. In a knitting-machine, in combination, a detent, having an open slot therein, one side whereof is provided with an incline K³, a rotatable cam, having a pin L', projecting therefrom, adapted to engage with the incline, K³, of the detent K, and slide the same end- 60 wise, a crank mounted on a shaft B⁵ and pro- vided with a pin at its free end for rotating the said cam, the bar J⁴, and the bar-actuating spring J⁷, substantially as and for the purpose specified. 65

5. In combination, in a knitting-machine, 70 the endwise-sliding bar J⁴, suitably support- ed and having a notch J⁸, therein, the bar-actuating spring J⁷, the sliding detent, adapt- ed to engage with the notch J⁸, in said bar J⁴, and having an open slot therein, one side 75 whereof is provided with an incline K³, a ro- tatable cam having a pin L', projecting there- from to engage with the incline K³ of the de- tent K, and draw it out of engagement with said bar J⁴, a spring for holding the detent 80 K, when normal, in engagement with said bar J⁴, and a crank suitably mounted and provided with a pin M' for rotating said cam, substantially as and for the purpose specified. 85
